burg, Pa., a corporation of Delaware

Application April 13, 1951, Serial No. 220,764

14 Claims. (Cl. 236—15)

1

This invention relates to automatic controls for appliances such as clothes dryers and more particularly to gas burning appliances of the described type.

Patent No. 2,533,982 discloses a domestic clothes dryer having a motor driven shell or drum in which the clothes are loaded for the drying operation which results when heated air is circulated through the load by a fan or blower. The source of heat comprises a main gas burner with which is associated the usual automatic pilot control for preventing the escape of unburned fuel together with electric ignition for the pilot burner and an overtemperature shut-off device to prevent hazardous conditions.

The present invention seeks to improve the disclosure of the aforesaid patent by simplifying the starting operation and reducing the number of specialized parts to provide a novel combination. Thus, an automatic pilot control of the thermal fluid type is provided and requires no manual reset operation. An electric ignition device is so arranged as to be automatically de-energized following the starting operation and also requires no manual effort in this respect. A simple solenoid valve controls the flow of fuel to at least the main burner and is energized under control of the thermostat which also controls the motor-driven drum. The solenoid valve may also be controlled by the overtemperature shut-off device for further reduction in the number of parts or a separate control may be provided for this purpose.

Other objects and advantages will become apparent from the following description taken in connection with the accompanying drawings, wherein:

Fig. 1 is a schematic view of a domestic clothes drying apparatus embodying the invention;

Fig. 2 is a similar schematic view but showing a modified form;

Fig. 3 is a side elevation partly in section of the main thermostat control device shown in Figs. 1 and 2;

Fig. 4 is a front elevation of the control device with the cover removed;

Fig. 5 is a cross-section taken on the line V—V of Fig. 3, and

Fig. 6 is a top plan view of the structure shown in Fig. 3.

Referring more particularly to Fig. 1, a main burner 10 is shown for location in a clothes drying apparatus and from which heated air is circulated by a motor-driven fan or blower 12 through the usual shell or drum (not shown). The motor 14 which drives the blower 12 may also drive the shell or drum as is customary in the art.

The main burner 10 receives a supply of fuel from a main fuel pipe 16 in which is interposed

2

an automatic pilot control device 18. Electrically operable means in the form of an electro-magnetic or solenoid valve 20 is also interposed in the main fuel pipe 16 for controlling the supply of fuel to the automatic pilot control device 18. The usual manually operated cock 22 is provided for controlling the supply of fuel in the main fuel pipe 16 to the solenoid valve 20.

Automatic pilot control device

The control device 18 comprises a casing 24 having an inlet 26 for one end of the main fuel pipe 16 and an outlet 28 for the opposite end thereof. A main valve seat 30 is formed in the casing 24 and has an opening 32 communicating with the outlet 28. A valve member 34 is co-operable with the valve seat 30 for controlling the passage of fuel between the inlet 26 and the valve opening 32 and is biased by a coil spring 36 into engagement with the valve seat 30.

A valve stem 38 projects from the valve member 34 through the casing 24 and into a cover member 40 for the casing 24. Supported in the cover member 40 is an actuating element 42 of a liquid type thermostat having the usual capillary tubing 44 and bulb element 46 associated therewith. The bulb element 46 is located to be heated by the flame of a pilot burner 48 which is located in lighting proximity of the main burner 10. The pilot burner receives a supply of fuel by way of a conduit 50 which is connected to the main fuel pipe 16 preferably between the gas cock 22 and the solenoid valve 20. The bulb element 46 is adapted to contain a quantity of thermal liquid, such as mercury, which becomes completely vaporized by the heat of the flame from the pilot burner 48 and causes expansion of the actuating element 42 under such conditions. The power so generated is adapted to be transmitted to the valve stem 38 for operating the valve member 34 to open position against the bias of the spring 36.

Interposed between the actuating element 42 and the valve stem 38 is a lever member 52 which is pivotally mounted in a bracket 54 carried by the cover member 40 adjacent the actuating element 42. The opposite end of the lever member 52 supports a plunger 56 which is slidably mounted in the casing 24 and projects into a switch housing 58 formed therein. The plunger 56 operatively engages a movable contact bar 60 located in the switch housing 58 and which is biased by a coil spring 62 into engagement with a pair of relatively fixed contacts 64, 66. The contacts 64, 66 are supported in the switch housing 58 by insulating plates 68, 70 respectively and may have suitable terminals (not shown) associated therewith.

A standby pilot valve member 72 is positioned in the casing 24 between the main valve member

34 and the switch housing 58 and is mounted on a valve stem 74 for reciprocable movement in the casing 24. Such movement is effected by engagement between the valve stem 74 and the lever member 52 intermediate the ends of the lever member 52. The valve member 72 is biased by a coil spring 76 into engagement with a valve seat 78 formed in the casing 24 and having an opening 80 therein. A standby fuel conduit 82 communicates at one end with the opening 80 and at the opposite end adjacent the main burner 10. A supply conduit 84 communicates at one end with the casing 24 for supplying fuel to the conduit 82 when the standby pilot valve member 72 is disengaged from its seat 78. The opposite end of the supply conduit 84 communicates with the main fuel pipe 16 preferably ahead of the gas cock 22.

Main thermostatic control

Referring now more particularly to Figs. 3, 4 and 5, a main thermostatic control device 85 comprises a housing 86 having a front cover 88 secured thereto and an open end within which a block 90 of insulating material is mounted. The cover 88 carries a centrally located nut 92 within which a threaded stud 94 of an operating handle 96 is mounted. The opposite end of the stud 94 is secured to an actuating element 98 of a liquid type thermostat having a capillary tube 100 and bulb 102 associated therewith. In this instance, the bulb 102 is located to respond to temperature conditions caused by operation of the main burner 10 and is not exposed to any flame. Consequently, the liquid fill may be of a nature to retain its liquidity throughout the operating range of the thermostatic device and may completely fill the bulb 102, capillary element 100 and actuating element 98 as is customary in such devices.

A button 104 carried by the actuating element 98 abuts a main actuating lever 106 which is provided at one end with a knife edge 108 seated in a pair of knife edged bearings 110 formed on a bracket 112 secured to the inner wall of the frame 86. The opposite end of the main actuating lever 106 is recessed at the center portion to provide a seat for one end of a tension spring 114, the other end of which is hooked in an apertured cross-bar 116 of an H-shaped control lever 118.

The two legs of the H-shaped control lever 118 are provided at one end with knife edges co-operating with spaced knife edged bearings 120 formed in a channel-shaped support 122 extending substantially parallel with the base of the housing 86. An adjusting screw 124 extends through the bottom wall of the housing 86 into engagement with the support 122 to adjust it on a pivotal mounting 126 located on the rear wall of the housing 86.

A pair of arms 128, 129 of insulating material are carried by the legs of the H-shaped control lever 118 opposite the knife edge bearings 120. The arm 128 is provided with a contact bridge 130. The contact bridge 130 cooperates with relatively fixed contacts 134, 135 mounted on the insulating block 88 and projecting exteriorly of the frame 86. In this embodiment, the contact 134 is provided with a terminal connection 138, while the contact 135 is adapted for permanent connection with a conductor 140. It will be apparent, however, that such arrangement can be modified as dictated by the circuit arrangement with which the control apparatus is used.

The structure so far described constitutes a snap-action mechanism by means of which the

control lever 118 can effect contact operation. Thus, as the liquid in the bulb 102 and the capillary tube 100 expands in response to temperatures prevailing at the point where the bulb 102 is located, the actuating element 98 will also expand and urge the free end of the main actuating lever 106 toward the knife edged bearing 110 of the control lever 118. Due to the tension of the spring 114, the control lever 118 and its arms 128, 129 will be moved to the left, as viewed in Fig. 3, with a snap-action as the actuating lever 106 moves over-center past a line between the respective bearings of the two levers. Such snap-action causes engagement of the contact bridge 130 and the contacts 134, 135 as will be apparent. In this embodiment, the contacts 134, 135 together with the contact bridge 130 constitute an auxiliary switching mechanism for the motor 14 as will hereinafter be apparent.

The closed position of the contacts 134, 135 will continue until the actuating element 98 starts to contract upon cooling of the bulb 102 whereupon a similar over-center snap-action will occur, but in the opposite direction to cause contact disengagement as the contact control lever 118 resumes its normal position as shown in Fig. 3. Separation of the levers 106 and 118 is prevented by a limit stop member 131 which is secured to the insulating block 90 and extends into the path of movement of the contact arm 129.

A pair of additional contacts 137, 139 are provided and are located to one side of the contacts 134, 135 as viewed in Figs. 4 and 5. These contacts 137, 139 are supported on an insulating plate 141 which is secured to the block 90 and extends into the housing 86. The contact 137 is adapted for permanent connection with a conductor 141 while the contact 139 has a terminal connection 143.

The contacts 134, 135 which cooperate with the contact bridge 130 to form the auxiliary motor switch as described are also provided with back contacts 144, 146 respectively in substantially the same plane as the contacts 137, 139. The back contacts 144, 146 form the main switching mechanism for the motor 14. These back contacts 144, 146 and the contacts 137, 139 cooperate with a pair of contact bridges 148, 150 respectively.

The contact bridges 148, 150 are mounted upon separate insulating contact arms 152 carried by flexible arms 154 mounted upon the opposite bifurcated ends of a secondary lever 156. A bracket 158 extends from the rear wall of the frame 86 and provides a pivotal mounting 160 for the secondary lever 156. A compression spring 162 is mounted between the secondary lever 156 and the inner wall of the frame 86 on the side of the pivotal mounting opposite the contact bridges 148, 150 thus serving to bias these contact bridges into and out of engagement with the contacts 144, 146 and 137, 139 respectively.

The secondary lever 156 is adapted to be operated during the snap-action movement of the main actuating lever 106. Thus, interengaging means on the main actuating lever 106 and the secondary lever 156 are provided and takes the form of a rocker 164 pivotally mounted on the bracket 158 and having a ramp 166 formed thereon for engagement by a projection 168 formed on the main actuating lever 106.

In order to maintain the contact bridges 148, 150 in engagement with their respective contacts, the bias of the spring 162 is overcome by a latching arrangement now to be described. The underside of the rocker 164 adjacent the lever 156

is provided with a notch portion 170 for engagement with the wall of a slot 172 formed in the lever 156. A manually operable plunger 174 extends through the cover 88 into the housing 86 for operative engagement with the lever 156 for overcoming the bias of the coil spring 162. When the lever 156 is thus tilted on its pivotal mounting 160, the rocker 164 is rotated in a counterclockwise direction by a coil spring 176 for engaging the notch 170 with the wall of the slot 172 as described. The plunger 174 is biased outwardly of the cover member 88 by a coil spring 178 and will return to such position upon release of manual pressure upon an enlarged end or button 180 of the plunger 174.

Secured to the exterior rear wall of the housing 86 is a housing 182 of insulating material. The housing 182 carries on one side thereof a pair of relatively fixed contacts 184, 186 with which a movable contact bridge 188 is adapted to cooperate. Contact 184 is adapted for permanent connection with a conductor 185 while the contact 186 carries a terminal connection 187. The contact bridge 188 is carried by a switch arm 190 of insulating material which is pivotally mounted at 192 on a bracket 194 carried by the housing 182. A coil spring 196, operative between the bracket 194 and the switch arm 190, serves to bias the latter and the contact bridge 188 into engagement with the contacts 184, 186. Disengagement of these contacts 184, 186 from the contact bridge 188 is effected by a pin 198 which extends between the contact arm 152 of the secondary lever 156 and the switch arm 190 through aligned apertures in the housing 182 and the frame 86. It is apparent that the contact bridge 188 is either disengaged or engaged relative to its described contacts simultaneously with the disengagement or engagement respectively of contact bridges 148, 150 with their described contacts.

The other portion of the housing 182 is provided with a pair of flexible switch arms 200, 202 carrying contacts 204, 206 respectively of their free ends. The switch arms 200, 202 are secured at the opposite ends to the housing 182 by screws 208 and are provided with separate terminal connections 210, 211. The contacts 204, 206 are adapted to cooperate with contacts 212, 214 respectively which are secured to the housing 182 by screws 215.

The flexible switch arms 200, 202 are adapted for conjoint operation to disengage from the contacts 212, 214. To this end, a projection 216 extends from the base of the housing 182 intermediate the switch arms 200, 202 and serves as a pivot point for one end of an actuating plate 218 of insulating material which underlies the switch arms 200, 202. The opposite end of the pivot plate 218 is engaged by an operating bar 220 which extends completely through the housings 182 and 86 and the front cover 88 for slideable movement relatively thereto. Such movement is effected by engagement of the projecting end of the pin 220 by a cam portion 222 formed on the underside of the dial 96. The cam element 222 is so oriented with respect to the dial 96 that the desired engagement with the operating bar 220 will occur when the dial is in the "Off" position. Cross-reference is made with respect to this thermostatic control device 85 to copending application of Weber and Kunzler, Serial No. 67,532 filed December 27, 1948 now Patent No. 2,564,868.

Electric ignition

An electric igniter 224 is shown on Fig. 1 as comprising a coil of wire adapted to be heated to incandescence by electric current supplied through a step down transformer 226 having its primary connected to line wires L1, L2. A suitable ballast 228 is provided in the secondary circuit to the igniter 224. The connections will be described in connection with the operation of the apparatus hereinafter.

In this embodiment, an overtemperature cut-out 230 of the thermally sensitive electric current is provided for opening the circuit to the solenoid valve 20 upon occurrence of hazardous conditions such as failure of the main thermostatic control device 85 to operate for maintaining safe temperature conditions in the appliance. As noted in connection with the ignition device, the circuit connections for the overtemperature cut-out 230 will be described in connection with the operation of the apparatus.

In the preferred embodiment, the fuel flow in conduit 50 to the pilot burner is under control of a pilot valve 232 which is carried on the casting 86 of the main thermostatic control 85. A projection 234 on the dial 96 is adapted for operative engagement with the stem portion of the pilot valve 232 for opening this valve whenever the dial is moved from the "Off" position to any temperature setting. It will be apparent that this pilot valve arrangement may be dispensed with as noted in the description of the operation of the apparatus.

Operation

The system is placed in operation by manual rotation of the cock 22 to open position whereupon fuel will flow in the main fuel pipe 16 as far as the solenoid valve 20. It may be assumed that the dial 96 is in the "Off" position so that the cam element 222 has forced the operating bar 220 inwardly to engage the actuating plate 218 and thus operate the flexible switch arms 200, 202 to disengage the contacts 204, 206 from the contacts 212, 214 respectively. Since line wires L1, L2 are connected to the terminals 210, 211 the circuit is broken on both sides of the line and movement of the dial 96 in a counterclockwise direction is required to disengage the operating bar 220 from the cam element 222.

Rotation of the dial 96 from the "Off" position to a preselected temperature setting will serve to cause longitudinal movement of the stud 94 to the left as viewed in Fig. 3. This also causes movement of the actuating element 98 and the button 104 to the left, but is insufficient to operate the main actuating lever 106 and cause snap-action of the control lever 118. Thus, the contact bridge 130 remains in position where the contacts 134, 135 are disengaged. However, the cam element 222 has moved out of engagement with the operating bar 220 so that the latter no longer causes disengagement of the contacts 204, 206 from contacts 212, 214 respectively.

The button 104 is then operated to cause the plunger 174 to engage and move the lower end of the secondary lever 156 on its pivot 160 thus overcoming the bias of the spring 162 and permitting the spring 176 to tilt the rocker 164 and engage the notch 170 with the wall of the slot 172. The secondary lever 156 is thus latched in its forward position with the contact bridges 148, 150 in engagement with the contacts 144, 146 and 137, 139 respectively. Due to the forward movement of the secondary lever 156 the contact bridge 188

is simultaneously moved by the contact arm 190 under bias the spring 196 into engagement with the contacts 184, 186 as previously explained.

A circuit is now made from the line wire L1, terminal 210, conductor 185, contact 184, contact bridge 188, contact 186, terminal 187, wire 238, contact 66, contact bar 60, contact 64, wire 238, primary of transformer 226, wire 240, overtemperature cut-out 230, wire 242, terminal 143, contact 139, contact bridge 150, contact 137, conductor 141, and terminal 211 to line wire L2.

Since the transformer 226 is now energized, a circuit for the igniter 224 is now established which may be traced from one terminal of the secondary of the transformer 226, wire 244, one terminal of ballast 228, wire 246, igniter 224, wire 248, opposite terminal of ballast 228 and wire 250 to the other terminal of the secondary of transformer 226. The dial 96 having been rotated to a selected temperature setting, the projection 234 thereon has operated the pilot valve 232 and the fuel flowing from the pilot burner 48 is ignited by the igniter 224.

Simultaneously with the establishment of the igniter circuit, the solenoid valve 20 becomes energized through a parallel circuit which may be traced by wire 252 connected at one end to wire 248 and at the opposite end to one terminal of the solenoid valve 20 and by wire 254 which is connected at one end to wire 236 and at the opposite end to the other terminal of the solenoid valve 20. Consequently, fuel now flows in the main fuel pipe 16 to the automatic pilot control device 18 where it enters through the inlet 26. When the bulb 46 of the liquid type thermostat becomes sufficiently heated by the flame from the pilot burner 48, the actuating element 42 operates the valve stem 32 and causes the valve member 34 to move to open position against the bias of the coil spring 36. Fuel thus flows from the inlet 26 through the opening 32 to the outlet 28 of the automatic pilot control device 18 where it is ignited by the flame from the pilot burner 48.

The actuating element 42 in its expanded condition serves to rotate the lever 52 of the automatic pilot control device 18 counterclockwise in Fig. 1 and the stand-by pilot valve member 72 is thereby moved to open position. Fuel thus flows from the conduit 84 through the conduit 82 having its open end adjacent the main burner 10 and is ignited thereby. The stand-by pilot will continue to produce a flame as long as the stand-by pilot valve 72 is in open position. The counterclockwise movement of the lever 52 also serves to operate the plunger 56 to disengage the contact bar 60 from the contacts 64, 66 in the switch housing 58. Such operation opens the circuit of the primary of the transformer 226 and causes deenergization of the igniter 224 as soon as the pilot burner 48 has heated the bulb 46 sufficiently to expand the actuating element 42.

At the same time, a circuit for the motor 14 is established and may be traced by way of line wire L1, terminal 210, wire 256, motor 14, wire 258, terminal 138, contact 144, contact bridge 148, contact 146, conductor 140 and terminal 211 to line wire L2. Thus, by operation of the main motor switch the motor-driven drum and fan 12 commence operation as soon as the dial 96 and push button 180 are manipulated as previously described.

When the temperature in the drying appliance reaches that which has been preselected on

the dial then the control will operate thermostatically. That is, the bulb 102 is exposed to the heat of the main burner 10 and will respond thereto sufficiently to expand the actuating element 98 and cause overcenter snap-action of the control lever 118. The auxiliary motor switch comprising contacts 134, 135 and contact bridge 130 is thereby operated to closed position so that the circuit of the motor 14 previously traced is not broken. During such operation of the lever 106 the projection 168 of the main actuating lever 106 tilts the rocker 164 and disengages the notch 170 from the wall of the slot 172. The secondary lever 156 is thus disengaged and the contact bridges 148, 150 carried by this lever are thereby disengaged from their related contacts simultaneously with disengagement of the contact bridge 138 from its related contacts 184, 186 by operation of the pin 198.

Thus, the opening of the contacts 138, 186, causes deenergization of the solenoid valve 20 through the opening of the described circuit and fuel to the main burner 10 is cut-off. The main motor switch comprising contacts 148, 146 and contact bar 143 is also opened but the auxiliary switching means comprising contacts 134, 135 and contact bridge 130 serve to continue the circuit to the motor 14 as described and after the solenoid valve 20 moves to closed position in order to provide a cooling down period before the appliance becomes fully shut down. It is apparent that the control device can be adjusted so that upon a rise in temperature at the bulb 102, the auxiliary switch means for the motor 14 serve to close the contacts 134, 135 thereof just below the preselected setting. However, as long as engagement between the contacts 134, 135 and contact bridge 130 occurs substantially simultaneously with the disengagement of the other contacts due to the desired snap-action of the control lever 118 then the operation of the motor 14 will not be interrupted. When the temperature at the bulb 102 drops an amount corresponding to the differential of the thermostat, then the actuating element 98 contracts sufficiently to cause overcenter snap-action in the opposite direction. The auxiliary switching means is therefore opened and since the contacts 134, 135 are disengaged from the contact bar 143 then the motor 14 will cease to run.

In the described embodiment it is unnecessary to rotate the gas cock 22 to closed position in order to shut-off the fuel flow to the pilot burner 48. It is apparent that rotation of the dial 96 to "Off" position will serve to disengage the projection 234 thereon from the pilot valve 232 and fuel flow in the conduit 50 will cease.

In the event that the flame at the pilot burner 48 becomes extinguished during normal running conditions, then the bulb 46 will become cooled and the actuating element 42 of the automatic pilot device 18 will contract. Consequently, the lever member 52 will be rotated in a clockwise direction under bias of the pilot valve spring 38 causing the pilot valve 34 to move to closed position relative to its seat 30. Flow of fuel to the main burner 10 is thus cut-off by operation of the automatic pilot device 18. It will be apparent, however, that fuel will continue to flow in the pilot conduit 50 to the pilot burner 48 and automatic reignition will occur if the main thermostatic control 85 is still in the original operating condition with the dial 96 in an "On" position and the push button 180 set in its inward position.

If during normal operation of the appliance, the dial 96 is turned from the "On" to the "Off" position then the main thermostatic control device 85 will operate to open the circuits for both the motor 14 and the solenoid valve 20. However, the pilot burner 48 will also become extinguished by such operation since the pilot valve 232 would no longer be held open. The appliance can be reloaded under such conditions and the system does not have to complete its full cycle.

It may occur that the dial 96 is rotated from "On" to "Off" position when the bulb 46 of the automatic pilot 18 is heated and then immediately to "On" position. This rapid recycling operation would first turn off the fuel to the main burner 10 and the pilot burner 48 and thereafter turn it on again without energization of the igniter. The automatic pilot control 18 would be unable to operate since the actuating element 42 would be expanded and maintaining the main valve member 34 open. However, since the standby pilot valve member 72 is also being maintained open, this burner would continue to produce a flame for igniting the main burner 10 and preventing escape of unburned fuel.

Should the temperature in the appliance exceed a predetermined safe limit as may happen in case of a defective thermostatic control device 85, then the overtemperature cut-out 230 would operate to open the circuit of the solenoid valve 20 and shut-off the supply of fuel to the main burner 10. The motor 14 would continue to run under such conditions.

Fig. 2 embodiment

The modified form shown in Fig. 2 is substantially the same as that previously described and similar reference numerals have been used for corresponding parts. The only essential difference is that the overtemperature control 230 shown in Fig. 1 is replaced by a liquid type overtemperature control 260 which serves to operate a valve device 262 interposed between the solenoid valve 20 and the automatic pilot control 18. As will be apparent, whenever the temperature at the bulb 260 exceeds safe limits the valve 262 will be operated to shut-off the fuel in the main fuel pipe 19 and thus discontinue operation of the main burner 10.

Various changes may be made in the details of construction and arrangement of parts without departing from the scope of the invention as defined in the appended claims.

I claim:

1. A control apparatus for fuel burning appliances having main and pilot burners and electrically operated heat distributing means, comprising in combination, an electric igniter for the pilot burner, control means responsive to a flame at the pilot burner for controlling the fuel supply to the main burner, switching means operably associated with said control means for controlling the energization of said igniter, electrically operable means for controlling the fuel supply to the main burner and adapted when energized to permit such supply, second switching means operable for controlling the energization of said electrically operable means and the heat distributing means, third switching means operable for controlling the energization of the heat distributing means independently of said second switching means, means responsive to a predetermined temperature condition caused by the main burner for operating said second and third switching means to cause deenergization of said

electrically operable means while the heat distributing means remains energized, and means operably associated with said third switching means for causing deenergization of the heat distributing means upon a variation in said predetermined temperature.

2. A control apparatus for fuel burning appliances having main and pilot burners and electrically operated heat distributing means, comprising in combination, an electric igniter for the pilot burner, control means responsive to a flame at the pilot burner and including a movable element for controlling the fuel supply to the main burner, switching means for controlling the energization of said igniter, connecting means between said movable element and said switching means for deenergizing said igniter after said flame has been burning for a predetermined period, electrically operable means for controlling the fuel supply to the main burner and adapted when energized to permit said supply, second switching means operable for controlling the energization of said electrically operable means and the heat distributing means, third switching means operable for controlling the energization of the heat distributing means independently of said second switching means, means responsive to a predetermined temperature condition caused by the main burner for operating said second and third switching means to cause deenergization of said electrically operable means while the heat distributing means remains energized, and means operably associated with said third switching means for causing deenergization of the heat distributing means upon a variation in said predetermined temperature.

3. A control apparatus for fuel burning appliances having main and pilot burners and electrically operated heat distributing means, comprising in combination, an electric igniter for the pilot burner, control means responsive to a flame at the pilot burner and including a movable element for controlling the fuel supply to the main burner, switching means biased to a closed position for controlling an energizing circuit for said igniter, connecting means between said movable element and said switching means for opening said circuit after said flame has been burning for a predetermined period, movable means biased to a closed position for controlling the fuel supply to the main burner, electromagnetic means for operating said movable means to an open position, a circuit for energizing said electromagnetic means and the heat distributing means, second switching means having open and closed positions for controlling said energizing circuit, manually operable means for closing said second switching means to establish said energizing circuit, third switching means having open and closed positions for controlling part of said energizing circuit independently of said second switching means, means responsive to a predetermined temperature condition caused by the main burner for opening said second switching means and substantially simultaneously closing said third switching means for deenergizing said electromagnetic means while the heat distributing means remains energized, and means operably associated with said third switching means for causing deenergization of the heat distributing means upon a variation in said predetermined temperature.

4. A control apparatus as claimed in claim 3 wherein a pilot valve member is provided for

11

controlling the fuel supply to the pilot burner, and means operably associated with said manually operable means for operating said pilot valve member during said controlling operations.

5. A control apparatus as claimed in claim 4 including means responsive to an abnormal condition caused by the main burner for terminating the fuel supply thereto.

6. A control apparatus as claimed in claim 5 wherein said condition responsive means includes a thermal cut-out in circuit with said electromagnetic means and exposed to the heat of the main burner for deenergizing said electromagnetic means under said abnormal condition.

7. A control apparatus as claimed in claim 5 including a standby pilot valve member, said connecting means extending between said movable element and said standby pilot valve member for operating the latter to open position upon expiration of said predetermined period.

8. A control apparatus for fuel burning appliances having main and pilot burners and electrically operated heat distributing means, comprising in combination, an electric igniter for the pilot burner, control means including a main valve member movable between positions for controlling the fuel supply to the main burner, thermally responsive means located to be heated by the pilot burner and operable when heated for moving said main valve member to a fuel supply position, a standby pilot valve having a movable valve member, switching means for controlling the energization of said igniter, connecting means extending from said main valve member to said standby pilot valve member and said switching means for operating said standby pilot valve member and deenergizing said igniter after said flame has been burning for a predetermined period, electrically operable means for controlling the fuel supply to the main burner, a thermostatic control switch in circuit with said switching means and operable for controlling the energization of said electrically operable means and the heat distributing means in accordance with temperature conditions caused by the main burner, manually operable means for adjusting said control switch for said controlling operations, and means for connecting said standby pilot valve to receive a fuel supply irrespective of the deenergized condition of said electrically operable means.

9. A control apparatus as claimed in claim 8 wherein a pilot valve member is provided for controlling the fuel supply to the pilot burner, and means operably associated with said manually operable means for operating said pilot valve member during said controlling operations.

10. A control apparatus for fuel burning appliances having main and pilot burners and electrically operated heat distributing means, comprising in combination, an electric igniter for the pilot burner, control means responsive to a flame at the pilot burner for controlling the fuel supply to the main burner, switching means operably associated with said control means for controlling the energization of said igniter, electrically operable means for controlling the fuel supply to the main burner and adapted when energized to permit said supply, a thermostatically controlled switch operable for controlling the energization of said electrically operable means and the heat distributing means in accordance with a predetermined temperature condition caused by the main burner, a second thermostatically controlled switch operable for controlling the energization

of the heat distributing means in accordance with a predetermined variation in said temperature condition, and means responsive to an abnormal condition caused by the main burner for terminating the fuel supply thereto.

11. A control apparatus as claimed in claim 10 wherein said condition responsive means includes a thermal cut-out in circuit with said electrically operable means and exposed to the heat of the main burner for deenergizing said electrically operable means under said abnormal condition.

12. A control apparatus for fuel burning appliances having main and pilot burners and electrically operated heat distributing means, comprising in combination, an electric igniter for the pilot burner, control means including a main valve member movable between positions for controlling the fuel supply to the main burner, thermally responsive means located to be heated by a flame at the pilot burner and operable when heated for moving said main valve member to a fuel supply position, a standby pilot valve having a movable valve member, switching means for controlling the energization of said igniter, connecting means extending from said main valve member to said standby pilot valve member and said switching means for operating said standby pilot valve member and deenergizing said igniter after said flame has been burning for a predetermined period, electrically operable means for controlling the fuel supply to said automatic pilot means, second switching means operable for controlling the energization of said electrically operable means and the heat distributing means, third switching means operable for controlling the energization of the heat distributing means independently of said second switching means, means responsive to a predetermined temperature condition caused by the main burner for operating said second and third switching means to cause deenergization of said electrically operable means while the heat distributing means remains energized, manually operable means for adjusting said temperature responsive means for said controlling operations, and means for connecting said standby pilot valve to receive a fuel supply irrespective of the deenergized condition of said electrically operable means.

13. A control apparatus as claimed in claim 12 wherein said third switching means has means operably associated therewith for causing deenergization of the heat distributing means upon a variation in said predetermined temperature, and means responsive to an abnormal condition caused by the main burner for terminating the fuel supply thereto.

14. A control apparatus as claimed in claim 13 wherein a pilot valve member is provided for controlling the fuel supply to the pilot burner, and means operably associated with said manually operable means for operating said pilot valve member during said controlling operations.
